UNITED STATES PATENT OFFICE.

ISAAC TUBBS, OF PIGGOTT, ARKANSAS.

MACHINE FOR EXTERMINATING BOLL-WEEVILS.

1,303,132.

Specification of Letters Patent.

Patented May 6, 1919.

Application filed January 27, 1919. Serial No. 273,327.

To all whom it may concern:

Be it known that I, ISAAC TUBBS, a citizen of the United States, residing at Piggott, in the county of Clay and State of Arkansas, 5 have invented new and useful Improvements in Machines for Exterminating Boll-Weevils, of which the following is a specification.

The object of my present invention is to provide a simple, easily operated and efficient 10 machine for mashing and thereby destroying boll weevils.

To the attainment of the foregoing the invention consists in the peculiar construction, novel combinations and adaptation of 15 parts as hereinafter described and definitely claimed.

In the accompanying drawings which are hereby made a part hereof:

Figure 1 is a side elevation of the machine 20 constituting the best practical embodiment of my invention that I have as yet devised.

Fig. 2 is a top plan view of the same.

Fig. 3 is a rear elevation of the machine.

Fig. 4 is an enlarged detail section showing 25 the relative arrangement of the guard employed in conjunction with the internal gear on one mashing wheel.

Fig. 5 is a detail transverse section taken through the blower of the machine.

Fig. 6 is a detail view of the clutch intermediate of one of the mashing wheels and the blower fan. 30

Similar numerals of reference designate corresponding parts in all of the views of the 35 drawings.

The main frame 1 of my machine may be of the construction shown or of any other construction compatible with the purpose of the invention. The forward portion of said 40 frame is connected to an axle 2, bearing ground wheels 3 and adapted for the connection of draft animals when such animals are to be employed for the movement of the machine.

The rear portion of the frame 1 is supported upon axles 4, and is equipped with a driver's seat 5. The axles 4 carries mashing wheels 6 which are spaced apart and are quite heavy. The treads of the wheels 6 are 45 made comparatively wide, and in the preferred embodiment of the invention the said wheels are eighteen inches in width by forty-eight inches in diameter.

Opposed to the upper rear portions of the 50 perimeters of the wheels 6 are scraping

blades 17 which are designed to serve the improved purpose of keeping the perimeters clear of dirt and other substance with a view to maintaining the efficiency of the wheels in mashing boll weevils. The said scrape 60 blades are connected by arms 8 to rock shafts 9 which are journaled in suitable bearings on the frame 1 and are provided with pedal levers 10 arranged in convenient proximity to the driver's seat 5.

At 11 on the frame 1 is carried the casing of the blower, the said casing containing a blower fan 12, and being equipped with a discharge spout 13 which is carried downwardly and has its eduction orifice arranged 70 at the inner side of the right hand fender as best shown in Fig. 3.

The fenders 14 are connected through suitable hangers 15 with the main frame and have their forward ends flared as illustrated. 75 The purpose of the fenders is to move at opposite sides of the plants so as to protect the limbs or branches, especially the lower limbs or branches of the plants from the mashing wheels 6.

One of the mashing wheels 6 and preferably the right hand mashing wheel is equipped with an internal gear 16, and the said internal gear 16 is connected through a train of gears 17 with the shaft of the blower 85 fan 12; the said gearing being of such type as to powerfully rotate the blower fan at a high rate of speed during the traverse of the machine.

Included in the said train of gearing is a 90 clutch, one member 17 of which is connected as shown with a pedal lever 18 so that when the said lever 18 is pressed forwardly the clutch member 17 will be moved against the action of its spring 19 so as to interrupt the driving connection intermediate the right hand mashing wheel and the blower fan 12.

At 20 is a guard designed and adapted to prevent portions of the plants from being caught in and injured by the teeth of the 95 gearing 16. The said guard is connected with and carried by the shaft of the right hand mashing wheel.

It will be apparent from the foregoing 100 that my novel machine is adapted to straddle the row of plants, and the fenders 14 are so arranged as to adequately protect the plants from the mashing wheels. Incidental to the traverse of the machine along the row 105 the blast of air under pressure from the 110

eduction orifice of the spout 13 serves to dis-
place the bolls from points about the stalks
of the plants into the paths of the wheels,
whereupon the wheels will pass over and
mash or crush the bolls with the result that
the boll weevils will be effectively exterminated.
It will also be apparent that the
boll weevils on the ground and in the paths
of the wheels will not be displaced by the
blast from spout 13.

The construction herein shown and de-
scribed is the best reduction to practice of
my invention that I have as yet devised, but
I would have it understood that in the future
15 practice of the invention various changes in
the form and relative arrangement of the
parts may be made within the scope of my
 appended claims.

Having described my invention what I
20 claim and desire to secure by Letters Patent
is:

1. A straddle-row boll weevil exterminat-
ing machine, comprising spaced mashing
wheels, and air-blast means for displacing
25 boll weevils from about the stalks of the

plants and moving the same into the paths
of the wheels.

2. A straddle-row boll weevil exterminat-
ing machine, comprising spaced mashing
wheels, spaced fenders for protecting the
plants from the wheels, and air-blast means
30 for displacing boll weevils from about the
stalks of the plants and moving the same into
the paths of the wheels.

3. A straddle-row boll weevil exterminat-
ing machine comprising a frame, steering
wheels connected therewith, comparatively
wide and spaced mashing wheels connected
with the frame, an internal gear in one of
35 said wheels, a guard in the wheel and com-
plementary to the gear, a blower casing car-
ried by the frame and having a depending
discharge spout, fenders spaced apart and
40 carried by the frame at the inner sides of the
mashing wheels, and a rotary fan in the
blower casing and connected through a gear-
ing with the internal gear of one mashing
wheel.

In testimony whereof I affix my signature.
ISAAC TUBBS.
